Primary Examiner — Manpreet Matharu*Assistant Examiner* — Mojtaba Tehrani(74) *Attorney, Agent, or Firm* — Ward and Smith, P.A.(57) **CLAIM**

The ornamental design for a disc-shaped tag for use in a wireless tracking system, as shown and described.

DESCRIPTION

FIG. 1 is a front perspective view of the disc-shaped tag showing my design;

FIG. 2 is a first side view thereof;

FIG. 3 is an opposing side view of FIG. 2;

FIG. 4 is a second side view thereof;

FIG. 5 is an opposing side view of FIG. 4;

FIG. 6 is a top view of the tag;

FIG. 7 is a bottom view of the tag; and,

FIG. 8 is a bottom perspective view of the disc-shaped tag. The broken line in the figure drawings represents unclaimed environment only and forms no part of the claimed design.

1 Claim, 6 Drawing Sheets(56)
